UNITED STATES PATENT OFFICE.

HENRY BARRY, OF CHICAGO, ILLINOIS.

BOTTLE-CAPPING MACHINE.

982,231.

Specification of Letters Patent. Patented Jan. 24, 1911.

Application filed October 6, 1909. Serial No. 521,280.

To all whom it may concern:

Be it known that I, HENRY BARRY, a citizen of the United States, residing at Chicago, in the county of Cook and State of Illinois, have invented a new and useful Bottle-Capping Machine, of which the following is a specification.

This invention relates to a hand-operated machine for capping milk bottles and the like.

The invention has for one of its objects to improve and simplify the construction and operation of apparatus of this character so as to be comparatively simple and inexpensive to manufacture, reliable and efficient in use, and so designed as to permit the capping of the bottles with despatch.

A further object of the invention is the provision of a bottle capping device including a holder for a plurality of bottles and a carrying lever mounted on and movable over the holder and supporting the cap-feeding means whereby the latter can be brought successively over the bottles on the holder for sealing the same with the caps.

Another object of the invention is to provide a bottle capping device including means for controlling the feed of the caps successively from the magazine tube, and means for centering and seating the caps in the bottles, said means being successively operated by a single lever.

With these objects in view and others, as will appear as the description proceeds, the invention comprises the various novel features of construction and arrangement of parts which will be more fully described hereinafter and set forth with particularity in the claims appended hereto.

In the accompanying drawings, which illustrate one embodiment of the invention, Figure 1 is a perspective view of the bottle-capping apparatus in operation. Fig. 2 is a vertical section of the pivot post for the carrying lever. Fig. 3 is an enlarged central section of the cap feeding and setting device, the section being taken on line 3-3, Fig. 5. Fig. 4 is a plan view showing the magazine tube removed and a portion of the casing broken away. Fig. 5 is a horizontal section on line 5-5, Fig. 3, with a portion of the actuating ring broken away.

Fig. 6 is a horizontal section on line 6-6, Fig. 3, looking in the direction of the arrow. Fig. 7 is a perspective view of the actuating ring for the cap feeding and cap setting devices. Fig. 8 is a fragmentary view showing the cap feeding and cap setting devices. Fig. 9 is a fragmentary sectional view similar to Fig. 6, showing the cap setting devices retracted. Fig. 10 is a perspective view of one of the cap feeding dogs. Fig. 11 is a perspective view of one of the devices for sealing the cap in the bottle.

65

Similar reference characters are employed to designate corresponding parts throughout the views.

Referring to the drawings, A designates the base of the machine which constitutes a holder for the bottle. This holder is in the form of a plate having a countersunk chamber 1 in the bottom of which are sockets 2 that form seats for the lower ends of the bottles to be capped. The machine is mounted on a table or other suitable support so as to be at a convenient height for the operator. At one side of the base is a bearing 3 having a vertically-disposed sleeve 4 in which is rotatably mounted a pivot 5 that has a bifurcated head 6 for receiving the end of a lever or carrier 7. The pivot extends downwardly below the bearing and is provided with a collar 8 between which and the bottom of the bearing 3 is arranged a compression spring 9 that encircles the lower end of the pivot, the spring thus allowing the pivot to have a limited upward movement in the bearing.

The lever 7 carries the capping device, which device is designated generally by B, and the fulcrum or pivot 5 is so located that the lever can be swung around on the pivot to the different bottles which are arranged, in one or more series, at different radial distance from the pivot. In the present instance, the sockets or seats 2 on the bottle holder are arranged in two series *a* and *b*, the latter being of greater radial distance from the pivot 5 than the former and each series is composed of two sockets. It is obvious, however, that any number of sockets may be employed. In order to adjust the lever so that the capping device B will

80

85

90

95

100

be disposed over either series, the lever 7 has a longitudinal slot 10 through which the pin or pindle 11 in the head 5 extends. The slot is of the same length as the distance between corresponding sockets of both sets. 5 This means, when the lever 7 is moved rearwardly until the pin 11 is at the inner end of the slot 10, the bottle capping device B will be disposed over the inner series of bottles, and when in this position, all the bottles of this series are capped and then the lever 7 is moved forwardly until the pin 11 is at the outer end of the slot 10, when the bottle capping device will be disposed over 15 the second series. At one side of the bottle holder or base A is arranged a bracket C which forms a rest for the lever and capping device when the bottles are being removed from or placed in position in the holder. There is an upwardly-extending stop 12 on the bracket C for arresting the movement of the lever in placing the same on the bracket. The central portion of the lever is formed into a split ring 13 that embraces the bottle capping device which is 20 readily secured thereto. The lever projects outwardly from the device and terminates in a handle 14. When the bottle capping device is positioned on a bottle, the handle 25 is pressed downwardly so as to firmly seat the device on the bottle, and during this movement, the spring 9 yields but exerts a downward tension to coöperate with the downward pressure on the handle to firmly 30 hold the bottle capping device in place during the insertion of the cap in the bottle. 35

The bottle capping device includes a cylindrical casing 15 from which rises a magazine tube 16 for holding the bottle caps or disks 17. The tube is open at its lower end 40 18, Fig. 3, and enters the casing, and surrounding the tube at the top of the casing is an annular flange 19 which rests on brackets 20, Figs. 3 and 4, located one hundred and twenty degrees apart. On these brackets are pivoted turn buttons 21 which engage over the flange 19 to clamp the magazine tube in place, the buttons having upwardly extending handles 22 for permitting 45 them to be conveniently turned. The magazine tube is closed at the top except for a small central opening 23 through which moves a plunger rod 24 that has at its lower end a weight plunger 25 that rests on the top of the column of caps in the tube for urging them downwardly. The outer end of the rod 23 has a knob 26 whereby the plunger can be raised and lowered and on the rod at a point outside the tube is a 50 cushioning spring 27. One side of the magazine tube is open for permitting the caps to be inserted, and this opening is closed by an approximately semi-cylindrical door 28 hinged at 29 along one edge and 55 provided with a spring clip 30 that forms a

handle for the door and is adapted to embrace the fixed part of the magazine tube to hold the door closed.

The casing 15 has secured to the top a ring 31 of L-shaped cross-section for fitting 70 around the casing 15 and closing the annular space between the flange 19 and top edge of the casing. As shown in Fig. 4, the horizontal flange or web of this ring 31 has recesses 32 to fit over the brackets 20 and this 75 ring is held in place by screws 33 which pass through the wall of the casing and screw into the brackets 20, as clearly shown in Fig. 3. The bottom of the casing is open so that the bottle to be capped can enter the 80 same. Within the casing is a fixed frame which is composed of a bottom ring 34 and a top ring 35 connected together by vertical posts 36, four of which are shown in the present instance. The rings are spaced 85 apart and rigidly held on the posts, the upper ends 37 of which latter project through openings 38 in the flange 19 of the magazine tube. The brackets 22, which are L-shaped, are fastened to the upper ring by 90 stud screws 39, as shown in Figs. 3, 4 and 8, so that these brackets rigidly secure the casing and frame together. The brackets have inturned lower ends which form guide lugs 40 for supporting the actuator designated 95 generally by C', which bears against the under side of the top ring 35. This actuator is an oscillatory lever having an annular head or ring 41 and a handle 42. The casing has a slot 43 at one side to permit the 10 lever to be turned for operating the cap-feeding and setting devices.

The means for controlling the feed of the caps consists of a plurality of dogs 44, one of which is shown in Fig. 10, and in the 10 present instance, three of such dogs are employed disposed one hundred and twenty degrees apart, and located in recesses 45 formed in the bottom side of the top ring 35, Figs. 4 and 8. Each dog has inwardly extending fingers 46 and 47 which are located one higher than the other a distance substantially equal to the thickness of one of the caps 17. The dogs are mounted to oscillate on vertical pivots 48, so that when the dogs are in 11 the full line position shown in Fig. 4, the lower fingers 46 will support the lowermost cap. When the dogs are turned to the position shown by dotted lines, Fig. 4, the lowermost 12 cap will be permitted to drop, and the upper fingers 46 will be projected inwardly under the column of caps for preventing them from dropping. It will thus be seen that the alternate swinging of the dogs back and forth causes the successive feed of the caps 13 one at a time. The dogs are actuated positively in both directions by arcuate flanges 49 on the top surface of the annular head or ring 41 of the actuating lever, Figs. 4 and 5. As the lever is turned, the outer corners 14

50 of the dogs, which corners project outwardly from the periphery of the ring 35, will be engaged by the ends of the flanges or abutments 49 so as to tilt the dogs from the full to the dotted line position, Fig. 4, and they will be maintained in this latter position throughout the movement of the lever in both directions. At the last part of the return movement of the lever, the projection portions or corners 50 of the dogs will be engaged by stop pins 51 for returning the dogs to their initial or full line position. The pivots for the dogs are in the form of countersunk screws 48 which pass upwardly through the ring 35, as shown in Fig. 3. After a cap has been fed by the dogs, the same drops freely through the device and lodges on the rim 53 of the bottle, Fig. 3, and it is forced on its seat 54 by a plurality of setting or seating devices located within the casing and operated during the movements of the lever after the feeding dogs have been actuated. These cap setting or seating devices consist of swinging arms 55 pivoted on the posts 36 in such a manner as to swing inwardly from an approximately tangential position to an approximately radial position. Each arm is turned by a torsional spring 56 coiled around its pivot post 36 with one end of the spring connected with the arm and the other end connected with the bottom ring 34. On the free extremities of the arms are depending cap-engaging fingers 57 extending parallel with the vertical axis of the device and so arranged as to engage over the cap after it has been dropped upon the bottle to depress the cap against its seat 54. For this purpose, the arms are moved downwardly after they have been swung inwardly to the position shown by dotted lines in Fig. 4. The lower ends of the fingers 57, when the arms are retracted, enter radial recesses 58 in the top surface of the bottom ring 34, and in these recesses are upstanding pins 59 that form stops for limiting the retracting movement of the arms by the fingers 57 engaging the pins.

The arms 53 are swung inwardly by arcuate flanges 60 arranged on the under side 50 of the ring 41, as clearly shown in Figs. 6 to 9, inclusive, which flanges engage projections 61 on the inner ends of the arms, and these projections ride along the inner surfaces of the flanges or abutments 60 during the continued movement of the actuating lever. After the arms are thus moved inwardly, cams 62 on the under side of the ring 41 engage the rounded portions 63 of the arms 55 and thereby depress the arms, 60 against the tension of the springs 56 until the parts are in the position shown in Fig. 3, where the said arms are shown held in depressed position by the cams 62. As the lever is returned, the cams 62 ride off the 65 arms so that the springs will cause the arms

and fingers to be raised, and during the continued movement of the ring, the arcuate flanges 60 will pass the projections 61 of the arms and allow the latter to be retracted by the springs, the springs thus acting by expansion and torsion to retract the arms 53. On the fingers 57 are triangular fins 65 that have their side edges beveled downwardly so as to grip the edge of the cap, should the same lodge on the bottle in an inclined position and thereby cause the cap to be centered as the arms are moved inwardly. As the arms move inwardly, the fingers engage over the top of the cap at four points near its periphery and cause the latter to be depressed upon its seat 54. The ring 41 is formed with arcuate slots 66 through which the pivot points 36 pass. The lower end of the magazine tube is recessed at 67 so as to permit the dogs to extend into the same to control the feed of the caps. As shown in Figs. 3 and 8, the bottom ring 34 is formed with an internal concaved seat 68 of such diameter as to receive the rim 53 of the bottle and by curving the seat, the bottle will automatically center the capping device thereon as the operating lever 7 is lowered.

After the capping device is placed on the bottle, the operator holds the lever 7 steadily in one hand and turns the lever 42 by the other. During the first part of the movement of the lever 42, the dogs 44 are actuated to drop the lowermost cap upon the bottle. During the intermediate part of the movement of the lever 42, the finger carrying arms 55 are thrown inwardly to center the cap on the bottle, and finally during the last part of the movement of the lever, the finger carrying arms are depressed so as to seat the cap in the bottle for sealing the same. The lever, of course, will be operated by a continuous movement to perform these three steps, namely, the depositing of the cap, the centering thereof, and the final seating of the cap in the bottle. On the return movement of the lever, the finger carrying arms are automatically retracted by their springs, while the cap feeding dogs are moved by the lever itself at the last part of its movement. It will thus be seen that the device is extremely simple and convenient to operate, as the only attention required on the part of the operator is to maintain the magazine supplied with caps and to position the device on the bottles one after another and turn the operating lever.

From the foregoing description, taken in connection with the accompanying drawings, the advantages of the construction and of the method of operation will be readily apparent to those skilled in the art to which the invention appertains, and while I have described the principle of operation of the invention, together with the apparatus which I now consider to be the best embodiment

thereof, I desire to have it understood that the apparatus shown is merely illustrative, and that such changes may be made when desired as are within the scope of the claims 5 appended hereto.

Having thus described the invention, what I claim as new, and desire to secure by Letters Patent, is:—

1. In an apparatus of the class described, 10 the combination of a holder having means for supporting a plurality of receptacles, a carrier located above the receptacles, a capping device mounted on the carrier, and means for connecting the carrier with the 15 holder, said means permitting a horizontal swinging movement of the carrier for applying the capping device to the receptacles successively.

2. In an apparatus of the class described, 20 the combination of a holder having means for supporting spaced rows of receptacles, a vertically and horizontally swinging carrier movable over the receptacles, a capping device mounted on the carrier, and means for 25 movably connecting the carrier with the holder for adjusting the device, to the receptacles of the rows successively.

3. In an apparatus of the class described, 30 the combination of a holder having means for supporting a plurality of receptacles, a vertical pivot, a horizontally swinging carrier slidably connected with the pivot, and a capping device mounted on the carrier.

4. In an apparatus of the class described, 35 the combination of a holder having means for supporting a plurality of receptacles, a vertical pivot, a vertically and horizontally swinging carrier slidably connected with the said pivot, and a capping device mounted 40 on the carrier.

5. In an apparatus of the class described, the combination of a holder having means 45 for supporting spaced rows of receptacles, a swinging carrier movable over the receptacles, a capping device mounted on the carrier, a pivot on which the carrier swings, and a connection between the pivot and carrier for permitting the device to be adjusted to the different rows of receptacles.

50 6. In an apparatus of the class described, the combination of a holder for a plurality of rows of receptacles, an upright pivot mounted on the holder, a swinging element movable over the holder, a slot and pin connection between the holder and pivot, and a capping device mounted on the element to be 55 adjusted to the various receptacles.

7. In an apparatus of the class described, 60 the combination of a holder including means for supporting a plurality of rows of receptacles, an upright pivot, a lever, means connecting the lever for permitting a longitudinal movement equal to the distance between adjacent rows of receptacles, and a 65 capping device carried by the lever.

8. In an apparatus of the class described, the combination of a holder for a plurality of rows of receptacles, a pivot on the holder, a lever, a slot in the lever of substantially the same length as the distance between the 70 row of receptacles, a pin on the pivot passing through the slot, and a capping device carried by the lever.

9. In an apparatus of the class described, 75 the combination of a holder for a plurality of receptacles, a pivot secured in fixed relation to the holder, a swinging element movable over the holder, a slot and pin connection between the pivot and element, and a capping device mounted on the element intermediate the ends thereof. 80

10. In an apparatus of the class described, the combination of a receptacle holder, a pivot yieldingly mounted on the holder, a lever connected with the pivot having a handle at the end opposite from the pivot for depressing the lever, a capping device on the lever, and means for exerting a downward pull on the pivoted end of the lever when the handle end of the latter is depressed for 90 positioning the capping device on a receptacle. 85

11. In an apparatus of the class described, the combination of a receptacle holder, a vertical pivot thereon, a spring for permitting the pivot to yield upwardly, a lever connected with the pivot having a handle at one end, and a capping device mounted on the lever at a point between the handle and pivot whereby the spring is compressed 95 when the handle end of the lever is depressed to position the device on the receptacle. 100

12. In an apparatus of the class described, the combination of a receptacle holder, a vertically movable and rotatable pivot thereon, an element swinging over the holder, a slot and pin connection between the pivot and element, a capping device carried by the element, and a spring on the pivot for permitting longitudinal movement thereof. 105 110

13. In an apparatus of the class described, the combination of a receptacle holder, a bearing at one side thereof, a pivot mounted in the bearing and movable longitudinally, a spring on the pivot for yieldingly resisting the longitudinal movement thereof, a lever movable over the holder, a hinged connection between the lever and pivot, and a capping device carried by the lever. 115

14. In an apparatus of the class described, 120 the combination of a receptacle holder, a bearing at one side thereof, a pivot mounted in the bearing and movable longitudinally, a spring on the pivot for yieldingly resisting the longitudinal movement thereof, a lever movable over the holder, a capping device carried by the lever, and a slot and pin connection between the pivot and lever for permitting longitudinal movement of the lever. 125

15. In an apparatus of the class described, 130

- the combination of a receptacle holder, a pivot thereon, a lever connected with the pivot to move over the holder and formed with a split ring at an intermediate point, 5 and a capping device mounted in the ring.
16. In an apparatus of the class described, the combination of a receptacle holder, a pivot mounted thereon, a lever having a longitudinal slot at one end and a handle at 10 the other and a ring at an intermediate point, a capping device mounted in the ring, and a pin on the lever passing through the slot for permitting longitudinal and vertical swinging movement of the lever.
17. In an apparatus of the class described, the combination of a receptacle holder, a capping device, a carrier for the device, and means for mounting the carrier on the holder to swing in a horizontal and a vertical plane 20 and move laterally for throwing the capping device toward or from the axis on which the carrier swings.
18. In an apparatus of the class described, the combination of a receptacle holder, a 25 capping device movable thereover, and means for mounting the device on the holder to permit the device to be swung in a vertical or horizontal plane and to be moved toward or from the axis on which it swings.
19. In an apparatus of the class described, the combination of a receptacle holder, a capping device, a swinging carrier mounted on the holder for supporting the device, and a bracket arranged at one side of the holder 35 for supporting the carrier when not in use.
20. In an apparatus of the class described, the combination of a receptacle holder, a pivot rising therefrom, a swinging lever mounted on the pivot, a capping device carried by the lever, and a bracket secured to the holder for forming a rest for the lever when the device is not in use.
21. In an apparatus of the class described, the combination of a magazine, means for 45 controlling the feeding of the caps from the magazine and for depositing a cap on a receptacle, means for centering and seating a cap after it has been placed on the receptacle, and a common actuator for the said means.
22. In an apparatus of the class described, the combination of a magazine, means for controlling the feeding of the caps from the magazine and for depositing a cap on a receptacle, means for centering and seating 55 the cap on the receptacle after the former has been deposited on the latter, and an actuator for successively operating the means by one movement of the actuator.
23. In an apparatus of the class described, 60 the combination of a magazine tube, means for centrally positioning the same over the receptacle to be capped, means between the tube and receptacle for controlling the feed of the cap from the tube, a plurality of devices arranged to engage over the cap and seat the same on the receptacle, and an actuator for the said means and devices.
24. In an apparatus of the class described, the combination of a magazine tube, a plurality of dogs arranged therein and each 70 having spaced fingers for controlling the feed of caps from the tube, and a rotary actuator encircling the discharge end of the magazine and movable back and forth for actuating the dogs. 75
25. In an apparatus of the class described, the combination of a magazine, a plurality of dogs therein for controlling the feed of devices from the chute, and an annular actuating device encircling the discharge end 80 of the magazine and mounted to rotate in opposite directions for oscillating the dogs to successively feed devices from the magazine.
26. In an apparatus of the class described, the combination of an annular support, dogs 85 pivotally mounted thereon and having cap-holding fingers extending inwardly from the support and portions extending outwardly therefrom, means for supporting a column 90 of caps over the dogs whereby the oscillation of the latter permits the caps to feed separately, and an actuator rotatable in opposite directions for engaging the outer portions of the dogs to move the same positively in both directions. 95
27. In an apparatus of the class described, the combination of an annular support, dogs pivotally mounted thereon and having fingers extending inwardly from the support and portions extending outwardly therefrom, means for supporting a column of caps 100 over the dogs whereby the oscillation of the latter permits the caps to feed separately, and an annular actuator rotatable on the support and having means for moving the 105 dogs.
28. In an apparatus of the class described, the combination of an annular support, a vertical magazine tube having its lower discharge end extending into the same and having recesses, devices mounted on the support and extending into the recesses for controlling the feed of caps from the tube, and a common actuator for moving the devices 110 in opposite directions to feed the caps successively. 115
29. In an apparatus of the class described, the combination of an annular support having recesses, a magazine tube arranged concentrically with the support, devices in the 120 recesses for controlling the feed of caps from the tube, an annular actuator rotatable on the recessed side of the support, means on the actuator for engaging the dogs to oscillate the same, and a handle connected with the actuator for moving the same back and forth. 125
30. In an apparatus of the class described, the combination of a supporting ring, a 130 magazine tube secured in fixed relation there-

- to, a casing secured to the ring, an annular actuator mounted in the casing and disposed concentrically with the ring, devices on the ring for controlling the feed of caps 5 from the tube and arranged to be operated by the actuator, and a handle exterior to the casing connected with the actuator for moving the same.
31. In an apparatus of the class described, 10 the combination of a frame, a casing, brackets for securing the casing to the frame, a magazine tube having an outstanding portion, buttons on the brackets for engaging the said outstanding portion to secure the 15 tube to the frame, and means within the casing for controlling the feed of devices through the tube.
32. In an apparatus of the class described, 20 the combination of a supporting ring, brackets thereon, an actuating ring rotatably supported by the brackets, a magazine, and devices operated by the actuator for controlling the feed of caps from the magazine.
- 25 33. In an apparatus of the class described, the combination of an upright magazine open at its bottom, an annular support therefor, devices on the support for controlling the feed of caps from the magazine, an 30 annular actuator disposed under the support and having upstanding members for engaging the devices to oscillate the same, and means for moving the actuator.
34. In an apparatus of the class described, 35 the combination of a magazine tube, a support therefor having an opening concentric with the tube, a plurality of devices on the support for controlling the feed of caps from the tube, each device comprising a 40 pair of spaced fingers for separating the lowermost cap from the pile in the tube as the device is oscillated, means under the support for seating the cap in the receptacle to be filled, and an actuator for moving the 45 devices to one position as the actuator is turned in one direction and for moving the devices in the opposite direction as the actuator is returned, said actuator serving to operate the cap seating means.
- 50 35. In an apparatus of the class described, the combination of a casing having a slot at one side, a magazine tube supported on the casing, devices within the casing for controlling the feed of caps from the tube, devices within the casing for setting the caps in the receptacles to be capped, and an oscillatory lever mounted in the casing and having a handle portion extending out of the slot for operating the said devices successively.
36. In an apparatus of the class described, 65 the combination of a casing, a receptacle-receiving seat at the bottom thereof, a cap-holding tube on the casing, oscillatory dogs in the casing for controlling the feed of caps from the tube, laterally-movable and compressible devices for seating the caps in the receptacles to be capped, and actuating means for the dogs and devices.
37. In an apparatus of the class described, 70 the combination of a supporting frame, a plurality of cap-centering and seating devices mounted thereon, a compression and torsional spring for retracting each device, and means for simultaneously actuating the 75 devices to center and seat a cap.
38. In an apparatus of the class described, the combination of a support, a plurality of independently mounted cap-seating devices arranged to engage a cap at spaced 80 points, and a common actuator therefor.
39. In an apparatus of the class described, the combination of a support, a plurality of independently mounted cap-seating devices arranged to engage a cap at spaced 85 points, and a rotary actuator for operating the devices simultaneously.
40. In an apparatus of the class described, the combination of a support, a plurality of laterally-swinging and compressible cap-seating devices, and an actuator for moving the devices first laterally and then depressing the same.
41. In an apparatus of the class described, 90 the combination of a support, a plurality of cap-seating devices spaced around a common axis and movable inwardly toward the axis and parallel therewith for seating a cap, and an actuator for the devices.
42. In an apparatus of the class described, 95 the combination of a support, a plurality of cap-seating devices spaced around a common axis and movable inwardly toward the axis and parallel therewith for seating a cap, an actuator for moving the devices to 105 seat the cap, and means for automatically retracting the devices as the actuator is returned.
43. In an apparatus of the class described, 110 the combination of a supporting frame open at its center to permit caps to pass therethrough, cap-centering and seating devices mounted on the frame and movable laterally into the opening thereof to engage over a cap and movable downwardly for seating the cap, and an actuator for the devices.
44. In an apparatus of the class described, 115 the combination of a supporting frame open at its center to permit caps to pass therethrough, cap-centering and seating devices mounted on the frame and movable laterally into the opening thereof to engage over a cap and movable downwardly for seating the cap, an actuator for the devices, and a combined compression and torsional spring 120 connected with each device for retracting the same to normal position.
45. In an apparatus of the class described, 125 the combination of a supporting frame open at its center to permit caps to 130

pass therethrough, devices arranged around the opening of the frame and movable from an approximately tangential to an approximately radial position and depressible after 5 reaching the latter position for seating the caps in the receptacles to be capped, and an actuator for the devices.

46. In an apparatus of the class described, the combination of a supporting 10 frame open at its center to permit caps to pass therethrough, devices arranged around the opening of the frame and movable from an approximately tangential to an approximately radial position and depressible after 15 reaching the latter position for seating the caps in the receptacles to be capped, an actuator rotatable in opposite directions on the frame, means on the actuator for moving the device inwardly and downwardly, 20 and separate means for retracting the devices as the actuator is reversed.

47. In an apparatus of the class described, the combination of a supporting frame, cap-centering and seating devices 25 mounted thereon, and an actuator having separate members for moving the devices laterally during the first part of the movement of the actuator and then depressing the devices during the remaining part of the 30 movement.

48. In an apparatus of the class described, the combination of a support open at its center to permit caps to pass therethrough, a plurality of cap-seating devices 35 spaced around the opening of the support and movable inwardly and downwardly, an actuator on the support, members on the actuator for moving the devices inwardly, and additional members on the actuator arranged 40 to engage the devices after they have been moved inwardly for depressing them to seat a cap.

49. In an apparatus of the class described, the combination of a support open 45 at its center to permit caps to pass therethrough, a plurality of cap-seating devices spaced around the opening of the support and movable inwardly and downwardly, an actuator on the support, members on the actuator for moving the devices inwardly, additional members on the actuator arranged 50 to engage the devices after they have been moved inwardly for depressing them to seat a cap, and means connected with the devices 55 for retracting the same during the return movement of the actuator.

50. In an apparatus of the class described, the combination of a supporting frame open at the center for permitting 60 caps to pass therethrough, laterally-movable and depressible arms mounted on the frame to swing into the opening thereof, devices on the arms for centering and seating a cap in the receptacle to be sealed,

and means successively acting on the arms 65 for first moving the same inwardly and then depressing them.

51. In an apparatus of the class described, the combination of a supporting frame open at the center for permitting 70 caps to pass therethrough, laterally-movable and depressible arms mounted on the frame to swing into the opening thereof, devices on the arms for centering and seating a cap in the receptacle to be sealed, 75 means successively acting on the arms for first moving the same inwardly and then depressing them, and means for automatically retracting the arms to normal position after the seating of the cap. 80

52. In an apparatus of the class described, the combination of a supporting frame having an opening for permitting caps to pass therethrough, laterally-swinging and depressible arms movable into the 85 opening, pivots on which the arms swing and are depressible, a helical spring on each pivot connected with the arm thereon to be tensioned by torsion and compression during the movement of the arm, devices on the 90 arm for seating a cap, and means for operating the arms against the tension of the spring.

53. In an apparatus of the class described, the combination of a supporting 95 frame constructed to permit caps to pass therethrough, laterally-movable and depressible elements arranged to engage over the cap after the same is deposited on the receptacle to be sealed, an actuator mounted 100 for rotary movement, arcuate flanges on the actuator arranged to engage the elements for moving the same laterally, cams on the actuator for engaging the elements while the same are engaged by the flanges to depress the elements, and means for retracting the elements after the cams and flanges 105 have disengaged them.

54. In an apparatus of the class described, the combination of a supporting frame, laterally-movable and depressible cap-seating devices, an actuator, arcuate members on the actuator for engaging the devices to move the same laterally, cams on the actuator for engaging the devices while they are held, in 110 their lateral position by the members to depress the devices, and springs subject to torsion and compression during the movement of the devices to retract the same after the cams and members disengage the devices. 115

55. In an apparatus of the class described, the combination of a supporting frame, vertically-disposed pivots, horizontally swinging and depressible arms on the pivots, cap centering and seating members depending from the arms, and a common actuator including separate sets of members, the first set being arranged to swing the arms laterally and 125

hold them in such position while the second set depresses the arms.

56. In an apparatus of the class described, the combination of a supporting frame, vertically-disposed pivots, horizontally swinging and depressible arms on the pivots, cap centering and seating members depending from the arms, a common actuator including separate sets of members, the first set being arranged to swing the arms laterally and hold them in such position while the second set depresses the arms, and means for automatically retracting the arms as the members are moved out of engagement therewith.

15 57. In an apparatus of the class described, the combination of a support, vertically disposed pivots thereon, horizontally-extending arms on the pivots, means for swinging the arms, means for depressing the arms, cap-seating members on the arms extending downwardly therefrom, and devices on the members for centering a cap before the same is seated by the members.

25 58. In an apparatus of the class described, the combination of a support, vertically disposed pivots thereon, a swinging arm on each pivot, springs on the pivots disposed under and connected with the arms to be placed under the tension as the latter move, members on the arms for seating a cap, means engaging the arms for swinging the same, and means for engaging over the arms for depressing the same against the tension of the springs to seat the cap.

35 59. In an apparatus of the class described, the combination of a plurality of parallel pivots, laterally extending arms mounted to swing and move longitudinally of the pivots, cap-centering devices on the arms, a torsional and compression spring on each pivot for retracting the arm, and separate means successively engaging the arms to swing and depress the same.

60. In an apparatus of the class described, the combination of a plurality of spaced parallel depressible elements for seating a cap, and means on the elements for first centering the cap before seating thereof.

61. In an apparatus of the class described, a plurality of parallel elements spaced apart to permit a cap to pass between them, means for moving the elements inwardly over the cap, and means for moving the elements into engagement with the cap for seating the same in the receptacle to be sealed.

62. In an apparatus of the class described, a plurality of parallel elements spaced apart to permit a cap to pass between them, means for moving the elements inwardly over the cap, means for moving the elements into engagement with the cap for seating the same in the receptacle to be sealed, and devices on the elements for centering the cap before the same is seated.

63. In an apparatus of the class described, the combination of spaced cap seating elements arranged to permit a cap to pass between them, means for moving the elements laterally over the cap to engage the latter adjacent its periphery, and means for simultaneously moving the elements longitudinally to seat the cap in the receptacle to be sealed.

70 64. In an apparatus of the class described, the combination of a supporting frame consisting of spaced rings and posts connecting the same, a plurality of cap-seating devices mounted on the posts, and an actuator carried by the frame and operatively associated with the devices for actuating the same.

75 65. In an apparatus of the class described, the combination of a supporting frame consisting of spaced rings, posts connecting the same, a plurality of swinging and depressible cap-seating devices on the posts, an actuator mounted on the frame to move in one direction for swinging the devices laterally and thereafter depressing the same, and springs on the posts for retracting the devices to normal position during the reverse movement of the actuator.

80 66. In an apparatus of the class described, the combination of a supporting frame composed of upper and lower rings spaced apart, pivot posts between the rings, cap-centering devices mounted on the posts and disposed between the rings, and an actuator disposed over the devices and under the upper ring and movable on the latter for actuating the devices.

85 67. In an apparatus of the class described, the combination of a supporting frame composed of upper and lower rings spaced apart, pivot posts between the rings, cap-centering devices mounted on the posts and disposed between the rings, an actuator disposed over the devices and under the upper ring and movable on the latter, members on the under side of the actuator for moving the devices laterally, and additional members on the under side of the actuator for depressing the devices while they are in engagement with the first members.

90 68. In an apparatus of the class described, the combination of a supporting frame composed of upper and lower rings spaced apart, pivot posts between the rings, cap-centering devices mounted on the posts and disposed between the rings, an actuator disposed over the devices and under the upper ring and movable on the latter, members on the under side of the actuator for moving the devices laterally, additional members on the under side of the actuator for depressing the devices while they are in engagement with the first members, and a torsional and compression spring for each device arranged to retract the same during reverse movement of the actuator.

69. In an apparatus of the class described, the combination of a supporting frame comprising spaced members having aligned openings through which caps are adapted to pass, a plurality of cap-seating devices disposed between the members and normally arranged in approximately tangential relation to the openings and movable laterally toward the axis of the frame, an actuator on the frame for moving the devices inwardly and thereafter depressing the same, and means for retracting the devices.

70. In an apparatus of the class described, the combination of a supporting frame comprising spaced members having aligned openings through which caps are adapted to pass, a plurality of cap-seating devices disposed between the members and normally arranged in approximately tangential relation to the openings and movable laterally toward the axis of the frame, an actuator on the frame for moving the devices inwardly and thereafter depressing the same, and means for retracting the devices, each device having a cap-centering means on its lower extremity for centering the cap before seating the same.

71. In an apparatus of the class described, the combination of a supporting frame composed of upper and lower rings connected together, a bottle-engaging seat on the lower ring, a plurality of cap-seating devices disposed between the ring normally above the seat, means for feeding a cap past the devices, means for moving the devices inwardly over the cap, and means for engaging the devices with the cap for seating the same.

72. In an apparatus of the class described, the combination of a supporting frame composed of upper and lower rings connected together, a bottle-engaging seat on the lower ring, a plurality of cap-seating devices disposed between the ring normally above the seat, means for feeding a cap past the devices, means for moving the devices inwardly over the cap, means for engaging the devices with the cap for seating the same, and laterally-extending fins on the lower ends of the devices having their outer side edges beveled downwardly to engage the periphery of the cap for centering the same on the bottle.

73. In an apparatus of the class described, the combination of a supporting frame consisting of a lower bottle-engaging ring and an upper ring spaced therefrom, pivot posts passing through the rings and secured thereto, cap-feeding devices on the upper ring, cap-centering devices disposed between the rings, and an actuator common to both devices and rotatably mounted on the upper ring.

74. In an apparatus of the class described, the combination of spaced upper and lower

rings having a common axis, devices on the upper ring for feeding caps, devices supported by the rings for seating the caps fed by the first devices, and a common actuator mounted on the upper ring and having means for oscillating the first devices and for moving the second devices inwardly over a cap delivered by the first devices and finally depressing the second devices into engagement with the cap for seating the latter.

75. In an apparatus of the class described, the combination of a supporting frame composed of upper and lower rings, pivot posts connected with the rings and disposed parallel with the axis of the rings, cap-centering devices mounted to swing and move longitudinally of the pivots and spaced between the rings, cap-feeding devices on the upper ring, an annular actuator disposed under the upper ring to rotate back and forth thereon, means on the upper side of the actuator for operating the cap-feeding devices, and means on the lower side of the actuator for operating the cap-seating devices.

76. In an apparatus of the class described, the combination of a casing, a frame within the casing having upwardly-projecting members, a magazine tube having an annular flange provided with apertures for receiving the members, devices carried by the frame for engaging the flange to hold the tube on the members, and means for feeding caps from the magazine tube.

77. In an apparatus of the class described, the combination of a supporting frame, upwardly-extending members thereon, a magazine tube having a flange resting on the frame and provided with apertures through which the members extend, turn buttons on the frame for engaging the flange, and means for feeding caps from the magazine tube.

78. In an apparatus of the class described, the combination of a supporting frame, cap-seating devices, pivot posts for the devices having their upper extremities projecting above the frame, means for actuating the devices, a magazine tube having an apertured portion resting on the frame and receiving the upper ends of the pivot posts, and means for clamping the magazine tube on the frame.

79. In an apparatus of the class described, the combination of a supporting frame, cap feeding and seating devices on the frame, means for actuating the devices, a casing surrounding the frame, a magazine tube on the casing, means for removably clamping the tube to the frame, said tube having a side door, and a weight plunger in the tube adapted to rest on the column of caps within the tube.

80. In an apparatus of the class described, the combination of a casing, a handle projecting laterally therefrom, a lever rigidly

connected with the casing and extending therefrom, cap feeding and seating devices in the casing, means connected with the handle for operating the devices, a cap holder 5 extending upwardly from the casing, and a bottle seat at the bottom of the casing arranged axially in alinement with the cap holder.

In testimony, that I claim the foregoing as my own, I have hereto affixed my signature in the presence of two witnesses. 10

HENRY BARRY.
